DRAWING PRESS

Johan A. Muller, Dayton, Ohio, assignor to The Hydraulic Development Corporation, Inc., Wilmington, Del., a corporation of Delaware

Application December 22, 1941, Serial No. 424,000

8 Claims. (Cl. 113—45)

This invention relates to drawing presses and, in particular, to drawing presses comprising feeding means.

One object of this invention consists in the provision of a drawing press having a horizontally moving drawing plunger and an automatically operated feeding system for feeding the work piece to the drawing plunger.

It is another object of this invention to provide a drawing press having a feeding device for feeding the work piece, which is operated in timed relationship with the operation of the drawing plunger.

It is another object to provide a drawing press having an electrical circuit for controlling the forward and return movements of the drawing plunger, which circuit comprises controlling means for controlling a feeding device so as to actuate the latter in synchronism with the drawing plunger.

Still another object of the invention consists in the provision of a drawing press having a blank-holding plunger and a drawing plunger, and also comprises a work piece feeding member which is automatically moved toward and away from the working position, while means is provided to delay the retraction of the feeding member until after the work piece has been engaged by the blank-holding plunger or by the drawing plunger.

This application is a continuation in part of my copending application, Serial No. 275,707, filed May 25, 1939.

The above and other objects of this invention will appear more clearly from the following specification in connection with the accompanying drawings, in which:

Figure 1 diagrammatically illustrates a drawing press according to the invention in the position it occupies at the end of a working cycle.

Figure 2 is a view similar to Figure 1, but showing the elements of the press in the position they occupy when approaching the end of a drawing stroke.

Figure 3 is an electric system in connection with the press of Figures 1 and 2.

Figure 4 is an enlarged sectional view through the work holder feeding mechanism, showing the feeding member in its retracted position.

Figure 5 is an enlarged sectional view through the work piece feeding mechanism taken along the line 5—5 of Figure 4.

Figure 6 is a fragmentary view of a portion of Figure 4, showing the feeding member in advanced position.

Figure 7 shows a modification of Figures 1 and 2.

General arrangement

In general, the drawing press of this invention is an automatically operative press having a horizontally movable drawing plunger and a horizontally movable blank holder, with an automatic control system for automatically advancing and retracting these elements. In particular, the press is provided with an automatic feeding arrangement for feeding work pieces to the drawing plunger, which work pieces are preferably of an elongated shape.

Prior to this invention, in the manufacture of deep cylindrical seamless metal articles with a closed end, such as, for example, a cartridge case, or a hand fire extinguisher casing, it has been the practice to form a preliminary cup-shaped article from a flat blank of metal. Several successive operations have then been performed on this cup-shaped piece, each operation increasing the depth and decreasing the diameter thereof until the desired shape is obtained. To produce the preliminary work piece of shallow cup-shaped form from a flat blank, it has been found convenient to employ a vertical downwardly-acting press. Where the shape of the work piece is such that its length is considerably greater than its diameter, this elongated work piece becomes rather difficult to handle in a vertical position, particularly where it is desired to feed the work piece automatically to the drawing plunger.

It is for this reason that the drawing press of the present invention is constructed and arranged with the main platen and the blank holder platen movable in a horizontal direction and synchronized with a hydraulically actuated feeding device for feeding the elongated work piece to the drawing plunger for the subsequent drawing operations.

Structural arrangement

Referring to the drawings in detail, the horizontal drawing press of this invention comprises a main cylinder 10 having reciprocably mounted therein a piston 11 with a piston rod 12, which latter has connected thereto a main platen 13. The main platen 13 is slidably guided along guiding means of any standard design, not shown in the drawings. Also slidably guided along the said guiding means is a blank holder platen 14 which is operatively connected to the main platen 13 and movable relative thereto by means of blank holder plungers 15, which reciprocate in blank

holder cylinders 16 provided in the main platen 13.

Pressure fluid for actuating the press plunger 11 in its working and retraction strokes is provided by means of a pump 17, the pressure side of which is connected through conduit 18 with a four-way valve 19, while the suction side of the pump 17 is connected by means of a conduit 20 with a conduit 21 leading to a fluid reservoir or surge tank 22.

Also connected with the four-way valve 19 is a conduit 23 leading to the right end of the main cylinder 10. Connected with the opposite end of the main cylinder 10 is a conduit 24 which leads to the four-way valve 19.

A fourth conduit, namely conduit 25, connected to the four-way valve 19, leads to the tank 22.

The four-way valve 19 has a valve member 26, which is continuously urged, by means of a spring (not shown) into position for establishing fluid connection between conduits 23 and 25, while simultaneously connecting conduit 18 with the conduit 24. A solenoid 27 is adapted, when energized, to shift the valve member 26 into position for establishing fluid connection between the conduits 18 and 23, while simultaneously connecting the conduits 24 and 25 with each other.

The tank 22 is also connected with a conduit 28 comprising a pressure relief valve 29 which may be by-passed by a conduit 30 comprising a check valve 31. The conduit 28 communicates with a conduit 32 leading to the blank holder cylinders 16. Mounted on the blank holder platen 14 is a hollow blank holder plunger 33 adapted to enter a work piece 34 to be drawn and to clamp the same against a die 35.

Extending through the blank holder plunger 33 and connected to the main platen 13 is the drawing plunger 36 for drawing a portion of the work piece 34 into the die 35. The work piece 34 is fed into the path of the drawing plunger 36 by means of a feeder, generally designated 37, and shown in detail in Figures 4, 5 and 6, while only diagrammatically indicated in Figures 1 and 2.

Referring to Figure 4, the feeding mechanism 37 is mounted upon the portion 38 of the press bed by means of a bracket 39, connected to the portion 38 in any convenient manner, for instance by screws 40.

The bracket 39 is provided with machined guideways 41 upon which a slide 42 is reciprocably mounted. Associated with the slide 42 is a feed cup 43 mounted upon arms 44, which are pivoted to the slide 42 by means of pivots 45. The arms 44 are urged upwardly against the slide 42 by springs 46 mounted upon cap screws 47. This construction permits the feed cup 43 to yield in a downward direction through a limited distance, thus enabling the withdrawal of the feed cup from the machine beneath the work piece when the latter has been clamped by the tubular blank holder plunger 33 against the die 35.

The feed cup slide 42 is reciprocated in the guideways 41 by means of a double-acting piston 48 which is reciprocably mounted in a cylinder 49. The cylinder 49 is integral with or in any desired manner connected to the bracket 39.

In order to provide a control and proper timing of the operation of the feeding mechanism 37, the electrical control system of the press is provided with a normally open limit switch 50

mounted upon the feed slide cylinder 49 and adapted to be closed by the cam 51 when the feed cup 43 has advanced the work piece 34 to a position in which it is ready to be worked upon by the drawing plunger 36 and to be engaged by the tubular blank holder plunger 33. The cam 51 is connected to the slide 42 in any convenient manner, for instance by screws 52.

As will be seen from Figure 3, the switch 50, when closed, is adapted to establish connection between the solenoid 53 and the conduit 54 which, by closure of switch 55, may be connected with the main supply line 56. One end of the solenoid 53 is always connected with the main supply line 56a. Also connected with the main supply line 56a is the solenoid 27 which, by closure of the switch blade 53a pertaining to the solenoid 53, may be connected with the main supply line 56.

20 A second switch blade 53b is adapted, when closed, to connect the solenoid 53 with main supply line 56 through the normally closed limit switch 53 which is adapted to be opened by the arm 43a of the main platen 13.

25 The feeding mechanism 37 is provided with a chute, generally designated 37a, which comprises bottom and top members 57 and 58 respectively interconnected by substantially parallel links 59, 60 and pivots 61, 62. The links 59 form supporting side members which in turn are pivotally mounted upon the supports 63 and 64 secured to the bracket 39. This construction enables the bottom and top members 57 and 58 to be spaced relatively to each other by a distance most suitable to the particular work piece being drawn, this distance being adjustable by means of the adjusting screw 65 which passes through a lug 66 and is held thereagainst by a lock nut 67.

40 The forward end of the top member 58 is provided with a flexible finger 68 which serves to restrain the work piece 34 from leaving the cup 43 until after the work piece is engaged by the tubular clamping plunger 33 or by the drawing plunger 36, as the case may be.

45 The cylinder 49 of the feeding mechanism 37 is provided with pressure fluid from a pilot pump 69 for advancing and retracting the feed cup 43. Normally, the pilot pump 69 is structurally united with the main pump 17 and driven by a motor 50 common to both. However, for the sake of clarity, Figures 1 and 2 show the pilot pump 69 separated from the main pump 17.

The pilot pump 69 has its suction side connected to the conduit 21, while its pressure side is 55 connected by means of conduit 70 with a four-way valve 71. Also connected with the four-way valve 71 is a conduit 72 leading to the tank 22. A conduit 73 comprising a shutoff valve 74 has one end connected to the four-way valve 71, 60 while its other end communicates with one end of the feeding cylinder 49. The opposite end of the feeding cylinder 49 communicates with a conduit 75 comprising a check valve 76, and likewise connected to the four-way valve 71.

65 The valve 71 comprises a valve member 77 which, by means of spring 78, is continuously urged into position for establishing fluid connection between the conduits 70 and 73, while 70 simultaneously connecting conduits 72 and 75. However, when actuated by a cam member 79, the valve member 77 is shifted into position for establishing fluid connection between the conduits 70 and 75, while simultaneously interconnecting the conduits 72 and 73.

The cam 79 is rigidly connected to a control rod 80, having adjustably connected thereto a collar 81 adapted to be engaged by a sleeve 82 carried by an arm 83 which, in its turn, is connected to the main platen 13. Also connected to the control rod 80 is a second cam 84 with a groove 85, while a compressible spring 86 is interposed between the collar 82 and the cam 84. The cam 84 is adapted to engage a valve member 87, pertaining to a two-way valve 88, so as to establish fluid connection between a conduit 89 communicating with the valve 88 and the conduit 75, and a conduit 90 comprising a shutoff valve 91 and leading to the conduit 75. When the valve member 87 is not engaged by the cam 85, the spring 86 shifts the valve member 87 so as to interrupt fluid connection between the conduits 89 and 90.

Referring now to the embodiment shown in Figure 7, the same differs from that of Figures 1 and 2 in that the valve 88, instead of being operated by the cam 84, is replaced by a valve 88a, which is fluid pressure operated. The parts of Figure 7 corresponding to those of Figures 1 and 2 are, therefore, designated with the same reference numerals as in Figures 1 and 2, however, with the additional character *a*.

The valve 88a corresponds in its construction to the valve 88 with the exception that the valve member 87a has connected thereto a piston 96 reciprocably mounted in a cylinder 97 which is connected, by means of conduit 98, with the conduit 32. The cylinder 97 is provided with a bleeder opening 99.

Figure 7 furthermore differs from Figures 1 and 2 in that the cam 84 is omitted and the arm 83 is rigidly connected to the rod 80a.

Operation

Assuming that all parts of the press occupy the position shown in Figure 1, and that the pumps 17 and 69 are running, the operator, in order to start a working cycle of the press shown in Figures 1 and 2, closes the switch 55.

Since, in the position of Figure 1, the switch 50 is closed, closure of the switch 55 causes current to flow from the main supply line 56 through switches 55, 50 and solenoid 53 to the main supply line 56a. This causes energization of the solenoid 53 and, as a result thereof, the switch blades 53a and 53b move to their closing position.

Closure of the switch blade 53b establishes a holding circuit for the solenoid 53, which holding circuit comprises the main supply line 56, normally closed limit switch 93, switch blade 53b, solenoid 53 and main supply line 56a. Closure of the switch blade 53a establishes a circuit comprising the main supply line 56, switch blade 53a, solenoid 27 and main supply line 56a, thereby energizing the solenoid 27.

Energization of the solenoid 27 causes shifting movement of the valve member 26 into position for establishing fluid connection between the conduits 23 and 18, while simultaneously connecting conduit 24 with the conduit 25. Pressure fluid from the pump 17, therefore, flows through conduits 18 and 23 into the right end of the main cylinder 10 and moves the piston 11 toward the left. Fluid expelled from cylinder 10 passes through conduits 24 and 25 into the tank 22.

Leftward movement of the piston 11 causes the main platen 13 and the blank holder platen 14 to advance toward the work piece 34, while the arm 83, connected to the main platen 13, causes the sleeve 82 to engage spring 86 and, by means

of the latter and control rod 80, to move the cam 79 away from the valve member 71. As a result thereof, the valve 71 moves into position for establishing fluid connection between the conduits 70 and 75, while simultaneously connecting the conduits 72 and 73 with each other. This, however, has no effect at this time, since the check valve 76 prevents fluid in conduit 70 from passing through the said check valve into the feeding cylinder 49, while, at this time, the two-way valve 88 is closed. Shortly after the blank holder platen 14 has advanced to such an extent that the blank holder plunger 33 clamps the work piece 34 against the die 35 and holds it properly clamped in this position, the sleeve 82 shifts, by means of spring 86, the cam 84 into such a position that the groove 85 comes into alignment with the valve member 87 and causes the latter to click into said groove.

In this position, the valve member 87 establishes fluid connection between the conduits 89 and 90, so that fluid from the pilot pump 69 now flows through conduits 70, 75, 90 and 89 into the feeding cylinder 49. This fluid acts upon the feeding piston so as to cause the latter to withdraw the feeding cup 43 from beneath the work piece 34 clamped against the die 35, and to move the feeding cup 43 into the position shown in Figure 4. During this movement, a new work piece slides from the chute 31a into the cup 43.

As soon as the feeding slide 42 begins its retraction stroke, the cam 51 releases the switch 50, so that the latter opens. However, this has no effect on the energization of the solenoid 53, since the latter is held energized by the holding circuit comprising the main supply line 56, switch blade 53b, solenoid 53 and main supply line 56a. The piston 11, therefore, continues its advancing movement and causes the drawing plunger 36 to engage the bottom of the work piece 34 and to draw the same into the die 35. If the clamping pressure in the blank holder cylinders 16 exceeds a predetermined value, the excessive pressure is released through the pressure relief valve 29 into the tank 22.

When the drawing plunger 36 has reached the end of its drawing stroke, the platen arm 13a engages the switch 93 so as to open the same, thereby breaking the holding circuit for the solenoid 53. As a result thereof, the solenoid 53 becomes deenergized and the switch blade 53a opens, thereby deenergizing the solenoid 27.

The valve member 26 of the four-way valve 19 now moves into position for establishing fluid connection between the conduits 24 and 18, while simultaneously connecting the conduits 23 and 25. Fluid from the pump 17, therefore, now passes through conduits 18 and 24 into the left end of the main cylinder 10 and moves the piston 11 with the piston rod 12 and main platen 13 toward the right. This also causes rightward movement of the blank holder 14, which is prevented by means, such as connecting rods (not shown in the drawings) from being disconnected from the platen 13. In this way, the drawing plunger 36 and blank holder plunger 33 are withdrawn from the work piece, which may now be removed.

During this retraction stroke of the main platen 13, the suction effect created in the cylinders 16 causes fluid to flow from the tank 22 through the check valve 31 into the cylinders 16 and fill the same with fluid.

The retraction stroke of the blank holder platen 14 is limited by the stop 94, while the retraction

stroke of the press piston 11 is limited by engagement of the piston portion 95 with the right end of the main cylinder 10. When the piston 11 has reached this position, the cam 79 on the rod 80 has been moved by the arm 83 and collar 81 into the position shown in Figure 1, in which position the valve member 77 is actuated so as to again establish fluid connection between the conduits 70 and 73, while fluid connection is established between conduits 70 and 75. Therefore, fluid from the pump 69 again flows through conduit 73 into the feeding cylinder 49 in the manner described above, and moves the slide 42 with the cup 43 again into the path of the drawing plunger 36. The press is now ready for a new cycle.

While, for the sake of simplification, the limit switch 83 has been described as position actuated, it is, of course, understood that, if desired, the switch 83 may also be pressure operated and form a part of a pressure responsive device, such as a so-called tonnage control valve, for instance, of the type disclosed in U. S. Patent 2,224,957 to Ernst.

It is furthermore to be understood that, while the cycle of the press, as described above, is semi-automatic, the press may also be operated fully automatically. In this instance, it is merely necessary to provide a linkage which is actuated by the press platen at the end of its retraction stroke for closing the switch 55.

With regard to the operation of the embodiment shown in Figure 7, the latter is substantially the same as described in connection with Figures 1 and 2. However, when, according to Figure 7, the clamping plunger 33 has clamped the work piece 34 against the die 35 and a predetermined pressure has built up in the clamping cylinders 16, this pressure is conveyed through conduits 32 and 98 to the cylinder 97 where it acts upon the piston 96, thereby shifting the valve member 87a into position for interconnecting the conduits 89 and 90. Fluid pressure from the pilot pump 69 will then be conveyed to the cylinder 49 in the manner above described. The remainder of the working stroke is then carried out as previously described. When the main platen 13 starts its retraction stroke, the pressure in the clamping cylinders 16 drops beyond the predetermined pressure for actuating the piston 96, so that the spring 92 returns the valve member 87a to its initial position.

It will be understood that I desire to comprehend within my invention such modifications as come within the scope of the claims and the invention.

Having thus fully described my invention, what I claim as new and desire to secure by Letters Patent, is:

1. In a hydraulic press, a reciprocable press plunger for exerting shaping pressure on a work piece, a press bed, a die supported by said press bed for cooperation with said plunger, a work piece feeder, a work piece support yieldably connected to said feeder and movable thereby for feeding a work piece into the path of said plunger and holding said work piece between said die and said plunger, motor means operable to reciprocate said feeder, clamping means for clamping said work piece against said die while said work piece is supported by said work piece support, and means including a switch, an electric circuit containing said switch and a valve controlling the supply of fluid to said motor means and operated by a solenoid in said cir-

cuit, said means being controlled by the travel of said plunger toward said die subsequently to the actuation of said clamping means for causing said motor means to reverse the movement of said feeder to withdraw said work piece support from said work piece while said plunger continues its movement toward said die.

2. In a hydraulic press, a reciprocable press plunger for exerting shaping pressure on a work piece, a die arranged in alignment with said plunger for cooperation with the latter, a work piece feeder comprising a slide and a work piece support, said slide being operable to move a work piece in said support into the path of said plunger between the latter and said die and to hold said work piece in this position, fluid operable means associated with said slide for selectively causing the same to perform a feeding or a retracting stroke, clamping means operatively connected with said plunger for clamping said work piece against said die, while it is in said support, said clamping means, when in clamping position, preventing said support from being retracted in the same plane in which the feeding movement thereof is effected, and means yieldingly connecting said support to said slide to allow said support, in response to a retracting movement of said slide, to pass about said work piece.
3. In a hydraulic press, a movable press plunger, a die for cooperation with said plunger for exerting a shaping action on said work piece, hydraulic means for reciprocating said press plunger, a work piece feeder, a work piece support yieldably connected to said feeder and adapted to fully support a work piece, said work piece support being operable by said feeder so as to move a work piece on said support into a position between said die and said plunger, a switch responsive to the movement of a work piece by said feeder substantially into the said position, an electric circuit including said switch, a solenoid in said circuit and a valve actuated thereby for causing said plunger moving means to initiate a working stroke of said plunger, and hydraulic means for withdrawing said work piece support from said work piece while the latter is subjected to pressure created by said plunger.
4. In a hydraulic press, a reciprocable press plunger, a fluid source adapted to supply pressure fluid to said plunger for actuating the same, a work piece feeder comprising a slide and a channel or trough shaped work piece holder yieldably connected to said slide and adapted to support a work piece, said work piece holder being movable selectively into feeding position for placing a work piece on said work piece holder between said plunger and a work piece support, clamping means associated with said plunger for clamping said work piece against said support, a valve for controlling the supply of pressure fluid from said fluid source to said press plunger, a switch responsive to the arrival of said work piece feeder at a location near its feeding position, an electric circuit containing said switch, and a solenoid for actuating said valve to cause said press plunger to move into engagement with the work piece in said feeder to shape said work piece, and an electric circuit including a switch, a solenoid, a valve, and a piston controlled by said valve and connected to the feeder, said switch being operable in response to the movement of said clamping means into clamping position and said piston acting to

withdraw said feeder from said work piece while said plunger completes its working stroke.

5. In a hydraulic press, a reciprocable press plunger, a fluid source adapted to supply pressure fluid for operating said press plunger, a work piece feeder adapted to receive and carry a work piece, hydraulic means for moving said feeder into feeding position so as to hold a work piece carried by said feeder in the path of said press plunger, an electric control circuit operatively interconnecting said feeder-moving means with said plunger-moving means, an electric switch in said electric circuit responsive to the advancement of said feeder into said feeding position for altering the energization of said electric circuit to actuate said plunger-moving means for effecting a forward stroke of said press plunger, and means responsive to a predetermined travel of said plunger during said forward stroke for actuating said feeder-moving means to withdraw said feeder from said work piece while said plunger continues said forward stroke.

6. In a hydraulic press, a reciprocable press plunger, a fluid source adapted to supply pressure fluid for actuating said press plunger, a work piece feeder having a yieldable work piece holder for selectively placing a work piece into the path of said press plunger, said work piece holder being adapted to act as sole supporting means for said work piece and to hold the same in lifted position during the first portion of the working stroke of the press plunger, clamping means for clamping said work piece in said lifted position while the work piece is still supported by said feeder, a hydraulic ram for reciprocating said work piece feeder, a hydraulic circuit for supplying pressure fluid to said ram, a valve, an electric circuit containing a switch and electrical devices for actuating said valve, said switch being operable in response to the travel of said

press plunger, said valve provided in said circuit for controlling the distribution of said pressure fluid to said ram and thereby the movement of said feeder in one or the other direction.

5 7. In a hydraulic press, a press plunger, hydraulic means for moving said press plunger, a work piece feeder for moving a work piece into the path of said press plunger and acting 10 as sole supporting means for said work piece during a predetermined portion of the pressing stroke of said plunger, means for reciprocating said work piece feeder, clamping means responsive to the travel of said press plunger for clamping 15 said work piece while in said feeder against a work piece support, means responsive to the completion of said clamping operation for withdrawing said feeder from said work piece, means controlled by said press plunger for causing a feeding operation of said feeder, and electric 20 means associated with said feeder and responsive to the feeding position thereof for starting a pressing operation of said press plunger.

25 8. In a hydraulic press, a press plunger, means for reciprocating said press plunger, a press bed, a die supported by said bed, a work piece feeder comprising a work piece holder for moving a work piece into a position between the latter and said die while supporting said 30 work piece in this position, clamping means for clamping said work piece against said die, means for conveying pressure to said clamping means for actuating the same so as to clamp said work piece against said die, and control means responsive to a predetermined clamping pressure exerted by said clamping means upon said work piece for withdrawing said work piece holder from said work piece without affecting the movement of said press plunger.

40

JOHAN A. MULLER.
